UNITED STATES PATENT OFFICE.

ROBERT L. DORAN, OF BAY CITY, MICHIGAN.

REGULATING DEVICE FOR LAMPS.

SPECIFICATION forming part of Letters Patent No. 546,282, dated September 10, 1895

Application filed April 29, 1895. Serial No. 547,528. (No model.)

To all whom it may concern:

Be it known that I, ROBERT L. DORAN, a citizen of the United States, residing at Bay City, in the county of Bay and State of Michigan, have invented certain new and useful Improvements in Regulating Devices for Lamps, of which the following is a specification, reference being had therein to the accompanying drawings.

10 The invention relates to that class of devices in which oil is fed to lamps under pressure from any desired source; and it consists in the peculiar construction of the regulating device for such oil-feed, whereby the lamps 15 will be maintained at a constant flame without danger of going out or overflowing.

The invention in particular consists in the peculiar construction of a valve comprising a stem, a port, and a compressible fibrous valve 20 or packing between the stem and the port, through which the oil is fed to the burner, the feed being controlled or regulated by compressing this packing more or less by the valve-stem.

25 The invention further consists in the construction of an automatic actuating device for such valve, controlled by the flame of the burner, all as more fully hereinafter described.

In the drawings, Figure 1 is a sectional elevation showing my improved device as in use. Fig. 2 is a similar elevation showing the automatic device for actuating the valve. Fig. 3 is a horizontal section above the thermostatic ring.

35 A is the lamp-fount, B the burner, and C the chimney, of a lamp of any known or usual construction.

D is an oil-supply pipe leading into the fount. In this pipe at any desired point, 40 preferably near the lamp, is the valve-casing E, having the partition or diaphragm with the concave seat a, in the bottom of which is the port b.

G is a valve-stem. H is the packing-box 45 through which the stem projects. I is a curved head on the lower end of the stem, above the concave seat in the diaphragm, and J is a fibrous valve or packing resting on the concave seat beneath the head I and 50 adapted to control the flow of the oil through the port b.

L is a shut-off valve in the oil-supply pipe.

The fibrous valve or packing I preferably make of mineral wool, asbestos, or similar material, which, while porous and fibrous, 55 has a certain amount of elasticity which will permit it to open and let the oil through when the pressure of the stem is removed.

The parts being thus constructed, they are intended to operate as follows: When the 60 device is not in use, the shut-off valve in the oil-supply pipe is closed. When it is desired to use it, that valve is opened and the oil will flow through the pipe and the valve-casing E into the fount, the flow through the valve- 65 casing being adjusted by raising or lowering the stem to make more or less pressure upon the fibrous valve. When the proper amount of oil is supplied through this valve—that is, when the proper adjustment is had—then the 70 lamp will continue to burn as long as oil is supplied, the controlling-valve admitting just the desired amount. I have found in practice that it is impossible to construct a valve-seating in the ordinary manner to have 75 a sufficiently fine adjustment for this use; but with the fibrous valve described the flow may be regulated to the smallest possible amount, just sufficient to maintain the lamp at the desired flame.

80 I may apply a controlling device for the valve, and that which I have shown consists of the brass ring M, supported on top of the perforated air-sleeve N and secured at one side only, as by the pin O. On the opposite side the 85 ring is connected to the bell-crank lever P, which at its opposite end is connected to the stem G. This stem in this construction slides through the stuffing-box H, and as the ring M contracts and expands will raise and lower 90 the stem, and thus increase or decrease the supply of oil, shutting it off as the flame gets too hot and opening the valve as it cools down, thus maintaining substantially a constant flame and a constant supply of oil to 95 the wick.

What I claim as my invention is—

1. The combination with a lamp, of a controlling device therefor, comprising a casing, a fibrous compressible packing therein, 100 through which oil is adapted to flow continuously, and a stem for compressing the packing to regulate the flow of oil therethrough, substantially as described.

2. A controlling device for lamps comprising a casing having a ported diaphragm, a fibrous valve or packing thereon through which oil is adapted to flow continuously, and a stem for compacting said valve to control the flow of oil therethrough.

3. The combination of the lamp fount, the oil supply pipe, the valve casing therein, the diaphragm F in the casing, having the concave ported seat α , the valve stem, the curved head I above the seat and the fibrous compressible valve or packing J between the head and seat, as and for the purpose described.

4. The combination with a lamp, of the fibrous valve through which oil is adapted to flow continuously, the stem for compressing the same to regulate the flow of the oil through the valve, the thermostatic ring M around the flame, and an operative connection therefrom to the stem, substantially as described.

In testimony whereof I affix my signature in presence of two witnesses.

ROBERT L. DORAN.
